HYDROCARBON CONVERSION

Roland B. Day and Elmer R. Kanhofer, Chicago,
Ill., assignors to Universal Oil Products Com-
pany, Chicago, Ill., a corporation of Delaware

Application July 26, 1940, Serial No. 347,755

6 Claims. (Cl. 196—52)

This invention relates to a process for the production of high yields of high octane rating gasoline and more specifically to a process involving both thermal and catalytic treatments whereby the hydrocarbon oil to be converted is treated under optimum conditions for conversion to high octane rating gasoline.

Catalytic cracking as ordinarily conducted does not employ recycling of insufficiently converted products to the conversion zone because, as has been found, such insufficiently converted hydrocarbons contain a high percentage of aromatics, cyclo-olefins, cyclo-diolefins, and diolefin hydrocarbon compounds, the tendency of which is to deposit great amounts of carbon or carbonaceous substances upon the catalyst particles, if recycled to the catalyst zone, resulting in a more rapid lowering of catalyst activity than is encountered when passing clean unconverted oils in contact with such catalysts. In order to reduce the formation of carbonaceous substances during conversion, resulting in shorter reactivation times and lower peak reactivating temperatures, it is usual to pass the hydrocarbon oil in contact with the catalyst only once and then thermally crack the insufficiently converted oils in a thermal cracking system. In a process employing both thermal and catalytic cracking in the manner above mentioned, the yield and octane of the gasoline product is good but is not as good as one might expect from a process wherein the catalytic recycle is also catalytically cracked.

In our invention involving both catalytic and thermal treatments the two steps have been combined in a novel and advantageous manner so that a relatively large proportion of the insufficiently converted hydrocarbons from the catalytic treatment is subjected to thermal treatment under conditions which favor the removal of the carbon forming constituents from the insufficiently converted hydrocarbons rather than thermal cracking, although some thermal cracking may occur. By this method compounds undesirable in catalytic cracking because of their tendency to form carbon, such as, for example, diolefins, aromatics, cyclo-olefins, and cyclo-diolefins are probably polymerized or undergo some treatment which converts them to higher boiling hydrocarbons which are removed as residue from the thermal treating system.

In one specific embodiment the invention comprises fractionating a heavy hydrocarbon oil charge, together with vaporous reaction products and catalytic conversion products both of which

are formed as hereinafter set forth, to separate fractionated vapors boiling substantially in the range of gasoline from the higher boiling oils, recovering the former, condensing said higher boiling oils as light and heavy reflux condensates in the fractionating zone, commingling a portion of said light reflux condensate with a light oil charging stock, heating and vaporizing the mixture, passing the heated vapors in contact with a mass of granular cracking catalyst, subjecting the catalytic conversion products to fractionation as hereinbefore set forth, subjecting the residual portion of said light reflux condensate and said heavy reflux condensate to separate thermal treatments, commingling the conversion products from both thermal treatments, separating non-vaporous liquid residue from the vaporous reaction products, recovering the former, and subjecting said vaporous reaction products to fractionation as hereinbefore set forth.

The primary object of this invention is to provide a combination of thermal and catalytic cracking wherein provisions are made for handling heavy distillation residues, such as, for example, topped or reduced crude oils and at the same time provide for thermally treating the insufficiently converted hydrocarbons from the catalytic cracking step to effect a removal of undesirable carbon forming constituents contained in the catalytic conversion products, since these materials if returned to the catalytic cracking step would result in the formation of large amounts of carbonaceous substances which deposit upon the catalytic material and lower the activity thereof.

The object of the invention may be accomplished in the following manner: Heavy charging oil comprising, for example, topped or reduced crude oil is fractionated, together with the catalytic conversion products and vaporous reaction products from the thermal treatment, to separate the gasoline vapors from the higher boiling oils. The higher boiling oil, comprising essentially reaction products, both catalytic and thermal, and the charging oil are condensed and collected as light and heavy reflux condensates. All of the light reflux condensate, but preferably only a portion thereof, may be heated and vaporized and the heated vapors subjected to catalytic cracking. In another manner of operation the light reflux condensate subjected to catalytic cracking is commingled with a relatively light hydrocarbon oil such as gas oil, naphtha, or kerosene introduced from an exterior source, the mixture heated and vaporized, and the resulting

vapors subjected to catalytic cracking, after which the catalytic conversion products may be subjected to fractionation as previously mentioned. The residual portion of the light reflux condensate is subjected to thermal treatment under conditions which favor the conversion of carbon forming constituents contained therein into heavier hydrocarbons which are removed as non-vaporous liquid residue in the vaporizing and separating step of the process. Heavy reflux condensate separated as above mentioned, consisting essentially of the heavy oil charge and the heavy ends of the conversion products, is subjected to thermal cracking in a heating oil and communicating reaction chamber. The conversion products from both thermal steps are commingled, the mixture supplied to a vaporizing and separating chamber wherein non-vaporous liquid residue is separated from vaporous reaction products, and the latter subjected to fractionation in the manner previously described.

In the preferred embodiment of the invention a relatively larger portion of the insufficiently converted hydrocarbons formed in both the catalytic and thermal treatments is returned to the thermal treatment as compared to the portion supplied to the catalytic treatment, although in some cases substantially equal amounts may be supplied to each step. By selecting conditions in the thermal treatment which will permit operating in this manner, theoretically at least, the insufficiently converted hydrocarbons make at least one pass through the thermal treating step before being subjected to cracking in the presence of catalytic material. In one or more passes of the insufficiently converted hydrocarbons through the thermal treating step, the undesirable carbon forming constituents which are formed in catalytic cracking are removed and recovered as non-vaporous liquid residue, whereas if these materials were returned to catalytic cracking a heavy deposition of carbonaceous substances on the catalytic material would result.

The accompanying diagrammatic drawing illustrates in conventional side elevation one specific form of the apparatus which may be employed to accomplish the objects of the invention.

Referring to the drawing, relatively heavy hydrocarbon oil such as, for example, reduced or topped crude oil or, when desired, a relatively wide boiling range hydrocarbon oil, such as crude oil, is supplied through line 1 containing valve 2 to pump 3. Pump 3 discharges through line 4 and when this stream of oil contains light fractions such as, for example, gasoline or fractions amenable to catalytic cracking in the vapor phase, this stream of hydrocarbon oil in line 4 may be directed through line 5 containing valve 6 into fractionator 7. However, when this stream of hydrocarbon oil contains no lighter hydrocarbons comprising either gasoline or hydrocarbons amenable to catalytic cracking, it may be directed through valve 8 into line 58 for treatment in the manner to be described.

The hydrocarbon oil supplied to fractionator 7 is subjected to fractionation therein in commingled state with vaporous reaction products formed in the subsequent thermal treating step and catalytic conversion products formed in the manner to be described to separate fractionated vapors boiling substantially in the range of gasoline from the higher boiling oils. Fractionated vapors separated as above mentioned leaving fractionator 7 are directed through line 9 containing

valve 10 to cooling and condensation in condenser 10. Distillate, together with undissolved and uncondensed gases from condenser 11, is directed through line 12 containing valve 13 into receiver 14 wherein the distillate and gases are collected and separated. Undissolved and uncondensed gases collected and separated in receiver 14 are removed therefrom by way of line 15 containing valve 16, recovered as a product of the process or subjected to any desired further treatment. A portion of the distillate collected and separated in receiver 14 is returned to the upper portion of fractionator 7 by well known means, not shown, as a refluxing and cooling medium while the residual portion thereof is removed from receiver 14 by way of line 17 containing valve 18, recovered as a product of the process or subjected to any desired further treatment.

Heavy oils separated from the lighter fractionated vapors in fractionator 7, including insufficiently converted hydrocarbons formed in both the thermal and catalytic cracking steps as subsequently described and in some cases the heavy portions of the charging oil, are condensed in the fractionator and separated into light and heavy reflux condensates, the light reflux condensate preferably comprising those hydrocarbons boiling below 650° F., while the heavy reflux condensate includes all hydrocarbons boiling above 650° F.

Light reflux condensate separated in fractionator 7 as above mentioned is directed through line 19 containing valve 20 to pump 21. Pump 21 discharges through line 22 and all of the light reflux condensate may be directed through valve 23 into line 27 and thereafter subjected to catalytic cracking in the manner to be described. Preferably, however, only a portion of the light reflux condensate in line 22 is directed through valve 23 to catalytic cracking while the residual portion thereof is subjected to thermal treatment in the manner to be described. The light reflux condensate supplied to line 27 by way of line 22 may be introduced alone to heating coil 29. However, in some cases, it may be commingled with a relatively light hydrocarbon oil, particularly amenable to catalytic cracking, such as, for example, gas oil, naphtha, or kerosene introduced from an exterior source by way of line 24, valve 25, pump 26, line 27, and valve 28 and the mixture supplied to heating coil 29. When desired, steam and/or light gaseous products, the latter comprising either those formed in the process or light gases introduced from an exterior source, are commingled with the hydrocarbon oil in line 27 to aid in substantially completely vaporizing said hydrocarbon oil and also as a means for reducing the total pressure on said oil during treatment. Heating coil 29 receives heat from furnace 30 whereby the oil introduced thereto is substantially completely vaporized and heated to a temperature ranging, for example, from 800 to 1200° F. preferably while maintaining said oil at a pressure ranging, for example, from substantially atmospheric to 200 pounds or more per square inch.

The heated reactants leaving coil 29 are directed through line 31 containing valve 32 into reactor 33 which contains catalytic material capable of effecting the desired conversion reaction. In the case here illustrated, reactor 33 may comprise, for example, a zone of the heat exchanger type wherein the catalyst is contained in a plurality of elongated tubular elements of relatively small diameter and wherein provisions

are made for passing some suitable heat convective medium such as combustion gases in contact with the exterior of said elongated tubular elements whereby to supply heat to the reactants during conversion and to effect cooling during reactivation of the mass of catalytic material. Reactor 33, on the other hand, may comprise a cylindrical vessel which is well insulated to reduce radiation losses and which contains one or a plurality of beds of catalytic material wherein the reaction may be accomplished substantially adiabatically.

In the catalytic cracking of hydrocarbons relatively large amounts of carbonaceous substances are formed which deposit upon the catalytic material thereby reducing its active surface and necessitating reactivation at periodic frequent intervals. The invention contemplates reactivating the used catalytic material in the usual manner, such as, for example, by passing oxygen-containing reactivating gases in contact with the used catalytic material and removing carbonaceous substances as combustion gases along with the spent reactivating gases. It is desirable, therefore, in order that the operation may be carried out as a continuous process to employ at least two reactors, and in some instances more than two reactors, so that while the catalytic material in one reactor is being used for effecting conversion of the hydrocarbon reactants the catalytic material in the other or others may be undergoing reactivation.

Catalysts which have been found to be effective in the catalytic cracking of hydrocarbon vapors may comprise pellets or granules of silica or other siliceous and refractory materials composed with compounds selected from the group consisting of alumina, zirconia, and thoria. In addition, the hydrosilicates of alumina, acid treated clays, or the like, have also been found to be effective in the cracking treatment of hydrocarbon vapors. Although the catalysts above recited are generally considered to be the preferred catalysts their use is not to be construed as a limiting feature, for various other catalysts well known to those in the art may be employed within the broad scope of the invention.

The conversion products leaving reactor 33 are directed through line 34 containing valve 35 into line 53, commingling therein with the vaporous reaction products formed in the manner to be described and the mixture supplied to fractionator 7 for treatment in the manner previously described. Fractionator 7, in the case here illustrated, together with the condensing and collecting equipment, may be operated under a superatmospheric pressure ranging, for example, from 25 to 200 pounds or more per square inch.

The residual portion of the light reflux condensate in line 22 is directed through line 36 containing valve 37 to pump 38 which discharges through line 39 containing valve 40 into heating coil 41, coil 41 receiving heat from furnace 42. Preferably also, in order that substantially all of the insufficiently converted hydrocarbons formed in both the thermal and catalytic treatments may be subjected to some thermal treatment, the quantity of insufficiently converted hydrocarbons subjected to the thermal treatment as light and heavy reflux condensates should be equal to if not greater than the amount of light reflux condensate directed through valve 23 in line 22 for catalytic cracking in the manner previously described.

Light reflux condensate passing through coil 41 is subjected to conditions of temperature and

pressure favorable to the conversion of the undesirable compounds present therein which are bad carbon formers when brought in contact with catalytic material whereby these materials are converted into heavier hydrocarbons and removed as liquid residue in a subsequent step of the operation. Temperatures to which the light reflux condensate may be heated in coil 41 will range from 800 to 1000° F., or thereabouts, while employing a superatmospheric pressure ranging, for example, from 100 to 1000 pounds or more per square inch. The heated products leaving coil 41 by way of line 43 may be directed through line 44 containing valve 45 into line 48 by means of which they are supplied to vaporizing and separating chamber 50 for treatment in the manner to be described. Preferably, however, the heated products in line 43 are directed through valve 46 into reaction chamber 47, commingling therein, in some cases, with other reaction products formed by the thermal cracking of the heavy reflux condensate in the manner to be described wherein additional time is allowed for the desired reaction to be accomplished. Reaction chamber 47 is preferably operated under a superatmospheric pressure substantially equal to or slightly less than that employed in coil 41 and may be insulated to reduce radiation losses therefrom, although no insulation appears in the drawing.

Reaction products leaving reaction chamber 47 comprising those formed in the thermal cracking of the light reflux condensate and/or those formed in the thermal cracking of the heavy reflux condensate are directed through line 48 containing valve 49 into vaporizing and separating chamber 50. In some cases, either or both of the reaction products formed in the thermal cracking of the light and heavy reflux condensates may by-pass reaction chamber 47 and, in such cases, these reaction products are supplied to vaporizing and separating chamber 50 by way of line 48, having been introduced to line 48 in the manner described. Chamber 50 is preferably operated at a substantially reduced pressure relative to that employed in the heating coil and/or reaction chamber whereby vaporous reaction products supplied thereto are substantially separated from the liquid reaction products and the latter substantially further vaporized to form a non-vaporous liquid residue which is removed by way of line 51 containing valve 52 and recovered as a product of the process or subjected to any desired further treatment. Vaporous reaction products supplied to chamber 50, together with vapors evolved therein are directed through line 53 containing valve 54 into fractionator 7 for treatment in the manner previously described.

Heavy reflux condensate comprising heavy ends of the conversion products supplied to fractionator 7 and, in some cases, heavy ends of the charging oil leaving fractionator 7 is directed through line 55 containing valve 56 to pump 57. Pump 57 discharges through line 58 containing valve 59 and, as above mentioned, when the heavy oil charge is not supplied to fractionator 7 it may be commingled with the heavy reflux condensate in line 58 having been introduced thereto by way of line 4 in the manner previously described and the resulting heavy oil mixture supplied to heating coil 60 which receives heat from furnace 61. The oil in passing through coil 60 is raised to a thermal cracking temperature ranging, for example, from 800 to 1050° F., or

thereabouts, preferably while being maintained at a superatmospheric pressure ranging from 100 to 600 pounds or more per square inch. The reaction products leaving coil 60 by way of line 62 may be directed through valve 63 into line 48 and thence into chamber 50 for treatment in the manner previously described. Preferably, however, the reaction products in line 62 are directed through line 64 containing valve 65 into reaction chamber 47 wherein they undergo prolonged treatment under the elevated conditions of temperature and pressure in the manner previously described.

When desired, instead of employing separate thermal treatment of the light and heavy reflux condensates the residual portion of the light reflux condensate supplied to the catalytic cracking step may be subjected to thermal treatment in commingled state with the heavy reflux condensate by directing the residual portion contained in line 22 through line 66 and valve 67 into line 55 where it combines with the heavy reflux condensate prior to the thermal treatment in coil 60.

An example of one specific operation of the process as it may be accomplished in an apparatus such as illustrated and above described is approximately as follows:

Heavy charging oil comprising a 25° A. P. I. gravity Mid-continent reduced crude oil is fractionated, together with catalytic conversion products and vaporous reaction products, both of which are formed in the manner to be described, to separate fractionated vapors of 400° F. end point from the higher boiling oils, including the heavy ends of the charging stock. The fractionated vapors are subjected to cooling and condensation and the resulting distillate and gas collected and separated.

The higher boiling oils separated from the fractionated vapors are condensed as light and heavy reflux condensates. A portion of the light reflux condensate is commingled with a 33° A. P. I. gravity gas oil in the volumetric ratio of 1:1 and the mixture heated and vaporized at a temperature of 950° F. The heated vapors under a pressure of approximately 30 pounds per square inch are passed in contact with a mass of synthetically prepared silica-alumina catalyst at a liquid hourly space velocity of approximately 2. The resulting catalytic conversion products are fractionated in the manner previously described.

The residual portion of the light reflux condensate not subjected to catalytic cracking is treated thermally at a temperature of approximately 850° F. and under a superatmospheric pressure of approximately 300 pounds per square inch. The conversion products formed by the thermal treatment of the light reflux condensate are supplied to a vaporizing and separating chamber for treatment in the manner to be described.

Heavy reflux condensate separated as above mentioned is subjected to thermal cracking in a heating coil and communicating reaction chamber at a temperature of 920° F. and under a superatmospheric pressure of 400 pounds per square inch. The conversion products formed in the thermal cracking of the heavy reflux condensate are commingled with the conversion products formed in the thermal treatment of the light reflux condensate and the mixture supplied to a reduced pressure vaporizing and separating chamber wherein vaporous reaction products

are substantially separated from the liquid reaction products and the latter substantially further vaporized to form a non-vaporous liquid residue which is recovered as a product of the process. Vaporous reaction products, together with vapors evolved within the vaporizing and separating chamber are subjected to fractionation in the manner previously described.

From an operation employing conditions as above mentioned one may obtain approximately 65.0% of 400° F. end point gasoline of approximately 76 octane number, 25.0% of non-vaporous liquid residue of approximately 10° A. P. I. gravity, the balance being principally carbon, gas, and loss.

We claim as our invention:

1. A process for the conversion of hydrocarbon oil which comprises catalytically cracking a relatively light hydrocarbon oil in substantially vapor phase, thermally cracking a heavier hydrocarbon oil, combining resultant cracked vapors from the cracking steps, fractionating to form light and heavy reflux condensate, recovering the fractionated vapors, returning one portion of the light reflux condensate to the catalytic cracking step, supplying said heavy reflux condensate to the thermal cracking step, thermally cracking another portion of the light reflux condensate, independently of the heavy reflux condensate, under conditions selected to convert undesirable carbon forming materials into liquid residue and to form cracked vapors, separating liquid residue from the cracked vapors, and fractionating the latter together with cracked vapors from the first mentioned thermal cracking step and the catalytic cracking step.

2. The process of claim 1 further characterized in that the light reflux condensate comprises a fraction having an end boiling point not substantially in excess of 650° F.

3. The process of claim 1 further characterized in that the light reflux condensate and the heavy reflux condensate subjected to thermal cracking comprises a larger quantity than the quantity of light reflux condensate returned to the catalytic cracking step.

4. A process for the conversion of hydrocarbon oil which comprises catalytically cracking said oil in substantially vapor phase, fractionating resultant cracked vapors together with other cracked vapors to form light and heavy reflux condensates, recovering the fractionated vapors, dividing the light reflux condensate into at least two portions each comprising hydrocarbons boiling over the entire boiling range of the light reflux condensate, returning one of said portions to the catalytic cracking step, subjecting another of said portions and said heavy reflux condensate to thermal cracking independently of each other under conditions in each of the thermal cracking steps selected to convert undesirable carbon forming materials into liquid residue and to form said other cracked vapors, combining resultant conversion products from the thermal cracking steps, separating liquid residue from the cracked vapors, and fractionating the latter as aforesaid.

5. A process for the conversion of hydrocarbon oil which comprises catalytically cracking said oil in substantially vapor phase, fractionating resultant cracked vapors together with other cracked vapors to form light and heavy reflux condensates, recovering the fractionated vapors, dividing the light reflux condensate into at least two portions each comprising hydrocarbons boiling over the entire boiling range of the light re-

flux condensate, returning one of said portions to the catalytic cracking step, subjecting another of said portions to thermal cracking under conditions selected to convert undesirable carbon forming materials into liquid residue and to form cracked vapors, combining said heavy reflux condensate with a hydrocarbon oil, heavier than the first mentioned oil, subjecting the mixture to thermal cracking independently of the light reflux condensate, combining resultant conversion products from the thermal cracking steps, separating liquid residue from cracked vapors, and subjecting the latter to fractionation as said other cracked vapors.

6. A process for the conversion of hydrocarbon oil which comprises catalytically cracking a relatively light hydrocarbon oil in substantially vapor phase, thermally cracking a heavier hydrocarbon, combining resultant cracked vapors from the cracking steps and fractionating the same along with a relatively wide boiling range hy- 20

drocarbon oil to form light and heavy reflux condensates, recovering the fractionated vapors, subjecting said heavy reflux condensate to thermal cracking as said heavier hydrocarbon oil, dividing said light reflux condensate into at least two portions, each comprising hydrocarbons boiling over the full boiling range of the light reflux condensate, subjecting one of said portions to catalytic cracking as said relatively light hydrocarbon oil, subjecting another of said portions to thermal cracking, independently of said heavy reflux condensate, under conditions selected to convert undesirable carbon forming materials into liquid residue and to form cracked vapors, separating liquid residue from the cracked vapors, and subjecting the latter to fractionation with the first mentioned cracked vapors.
